ELECTRONIC SPACE UNIT HUMIDIFIER

Charles V. Runkle, Detroit, Mich.

Application August 31, 1951, Serial No. 244,610

7 Claims. (Cl. 219—40)

1

This invention relates to humidifying devices, and has particular reference to a device for adding hot gaseous moisture to the air in a home, office, or other place of business or the like, and this application may be considered a continuation in part of my co-pending application, Serial No. 212,143, filed February 21, 1951.

An object of this invention is to generally improve devices of the character indicated and particularly to provide a control system for such a device, which is simple in construction, economical to manufacture and efficient in operation.

Another object of the invention is to provide a device of the character indicated which has a control mechanism constructed and arranged so that air may be trapped and released from the water as the unit is being charged with water from the main reservoir.

Another object of the invention is to provide a humidifying device for domestic purposes which is compact and highly portable and one in which almost any type of an open receptacle may be employed as the main reservoir, thereby reducing the cost of production of the device and by the same token broadening the horizon of its utility.

The foregoing and other objects and advantages of the invention will become more apparent as the description proceeds, reference being made from time to time to the accompanying drawings forming part of the within disclosure, in which drawings:

Fig. 1 is a vertical section taken through a device embodying the invention.

Fig. 2 is a top plan view of the device illustrated in Fig. 1.

Fig. 3 is a section taken substantially on the line 3—3 of Fig. 1.

In Patent No. 2,451,594 issued to Watson he disclosed the process of vaporizing a liquid by inserting a pair of spaced electrodes in the surface of the liquid, applying unlike potentials to the electrodes, and adjusting the spacing between the electrodes to a distance greater than the capillary spacing for the liquid and within the distance that can be bridged by a film of the liquid, and in my co-pending application hereinabove referred to, I disclose the manner in which the principle disclosed in the Watson patent could be utilized in a no-pressure space unit humidifier.

The instant invention improves the structure disclosed in my co-pending application and provides a greatly improved mechanism for controlling the flow of fluid from the principal reser-

voir to the heating compartment. This disclosure also teaches the manner in which a highly portable compact version of a humidifying device may be employed with a conventional type of water reservoir.

Referring now more particularly to the drawings, it will be understood that in the embodiment herein disclosed, the reference character 7 indicates a tray or shallow receptacle suitable for use as a reservoir for holding the liquid to be vaporized. The reservoir 7 should preferably be made of a non-conductive material. Positioned on the inside of the reservoir 7 and resting on the bottom 1A thereof, is a rectangular box like structure having a bottom wall 8, side walls 9 and 10, and end walls 11 and 12, all of which are made of a non-conductive material and are secured together in a water tight manner by any suitable means. The box like structure just described is adapted to receive measured amounts of water from the main reservoir 7, through the wall opening 13 and the inclined passageway 14 formed in the member 15, which is secured to the wall 10 of the box like structure previously described. The flow of the water from the reservoir 7 through the passageway 14 is controlled as hereinafter described:

At the upper end of the passageway 14, I provide a counterbore 16 which is normally covered by a semi-spherical element 17 made of pliable non-conductive material to which is secured a hollow spherical element 18 which is in communication with the member 17 through the passageway 19. The purpose of the elements 17 and 18 is to provide an insulating air space in passageway 16, in order to prevent the electrical current from traveling from the electrodes 32 and 33 into the water of the main reservoir 7, which might shock an attendant during the time of adding water to or refilling the reservoir 7. It will be understood that by manually lifting the handle 28 the rod 21 will be forced downwardly, collapsing the members 18 and 17. This forces the water out of the elements 14, 16 and 17 and permits air from the member 18 to enter the elements 14, 16 and 17 and to remain there so long as pressure is maintained on the rod 21. When the pressure is released from rod 21 the trapped air will then return to the member 18 and remain there until the next time the member 18 is collapsed. The elements 17 and 18 are suspended on a rod 21 which is pivoted at its upper end to a rocker arm 22, which in turn rocks on a pin 23 secured in the wall 10 of the box like structure previously described. The

rocker arm 22 is made of any suitable non-conductive material. Secured to the opposite end of the rocker arm 22 is a bent and rebent rod 24 which is provided with a terminal eye 25, which engages the outer periphery of an internally threaded spool like nut 26, which is secured to the end of an adjusting arm 27 which is rotatable about its longitudinal axis by the hand grip 28. The nut 26 engages the external threads 29 formed on another rod 30, at the lower end of which is secured a float 31. The rise and fall of the float 31 is controlled by means of adjusting the position of the nut 26 on the rod 30. This in turn controls the movement of the member 17. When the member 17 is lifted from the upper surface of the member 15, it permits water to enter the counterbore 16 and the passageway 14 and hence through the wall opening 13 into the lower portion of the rectangular box like member 8-12. When the member 17 is forced over the opening 16, the fluid in the passageways 13, 14, and 16 is moved downwardly permitting any air trapped in the passageway to escape into the opening formed between the member 17 and the member 15 which air may then escape into the member 18 through the passageway 19. A slide 27A extends through a slot formed in the wall 9 and is adapted to frictionally engage the rod 27 to lock the parts in closed position as shown in Fig. 1.

In order that this humidifying device may operate with utmost efficiency, it is very important that the water level in the box like structure 8-12 be controlled within somewhat exacting limits. It will be understood that the water level in the reservoir 7 must at all times be above the surface of the member 15 and that the water level in the box like member 8-12 previously described shall be sufficient to cover the lower ends of the conductive generator plates 32 and 33, which are respectively spaced from, as at 34, and 35, and secured to, as at 36 and 37 the non-conductive walls 38 and 39 of the generator. The generator plates 32 and 33 are highly conductive elements and serve as the electrodes for the generator. It will be noted that the conductive plate or electrode 32 has one or more cut-out portions 32A formed along the lower edge thereof. This reduces the surface area of the electrode 32 and its resulting potential.

Leads 40 and 41 are arranged to be connected to a source of 110 volt A. C. electric current. The side walls 38 and 39 and end walls 42 and 43 of the generator are secured to the underside of a top member 44, which is provided with an opening 45 which communicates with a stack 46, through which the vaporized liquid escapes into the atmosphere. The lower ends of the generator walls 38, 39, 42 and 43 rest upon the bottom 8 of the box like member 8-12. The side wall 38 of the generator has an opening 47 at the bottom so that liquid may enter the generator from the box like member 8-12. Spacers 48 of non-conductive material are positioned between the wall 11 (Fig. 2) of the box like member 8-12 and the wall 39 of the generator and spacers 49 are provided on the wall 38 of the generator and serve as guides for the reciprocating movement of the float 31.

The device functions as follows. The reservoir 7 is first filled with water to a suitable depth sufficient to cover the upper surface of the member 15. The locking slide 27A is then released from the rod 27 and the rod 27 is rotated about its longitudinal axis until the nut 26 is in a position

on the rod 30 to permit the rocking of the arm 32 to lift the member 17 from the member 15. This permits water to enter the passageway 16, 14, and 13 and flow into the box like structure 8-12. When the water level in the box like structure 8-12 reaches the required depth to cover the lower ends of the electrodes 32 and 33, the nut 26 is adjusted so that the float 31 will force the member 17 into contact with the member 15 to shut off further flow of water into the box like structure 8-12.

Electrical connection is then made with a suitable source of 110 volt A. C. electrical current and the device begins to function. Upon passage 15 of the current across the surface of the liquid, films of the liquid immediately commence to rise in rapid succession. These films bridge the space between the electrodes 32 and 33 and are arched upwardly. The current flows through the films 20 until the latter become vaporized. Both of the electrodes 32 and 33 become activated for a distance of several inches above the liquid level. The electrodes 32 and 33 are of such low resistance as to be practically unheated by the flow 25 of current through them. As the films become vaporized and rise through the interior of the generator, they are discharged into the atmosphere through the vapor stack 46. The temperature of the liquid in the box like member 8-12 30 remains cool so that the vaporization does not depend on heating of the mass of liquid as is the case with the usual water humidifier. The vapor emanating from the stack 46 is practically invisible and readily mixes with the air in the room. 35 The device will continue to function in the manner indicated so long as water is retained in the reservoir 7 and electric current is applied to the electrodes 32 and 33 of the generator.

Having described my invention, what I claim and desire to secure by Letters Patent is:

1. In a device of the character described in combination, a liquid reservoir of non-conductive material, a rectangular box like member of non-conductive material supported on the bottom of said reservoir, an electric vapor generator in said rectangular box like member, a non-conductive element on one of the outside walls of said box like member, said non-conductive element having an inclined passageway therein in communication with the interior of said box like element and said reservoir, a collapsible semi-spherical non-conductive element positioned over the upper end of said passageway and arranged, when collapsed, to force air into said passageway, whereby to prevent the electric current from the generator from reaching the liquid in the reservoir, a rod for supporting said semi-spherical element, a rocker arm for supporting such rod, a second rod supported by said rocker arm, and a float positioned in the said box like member and means for securing said float to said last named rod.

2. The structure defined in claim 1, in which said generator comprises a pair of closely spaced electrodes, the lower ends of which are arranged to be submerged in the liquid carried in said box like member.

3. The structure defined in claim 1, in which said generator comprises a pair of closely spaced electrodes arranged to be partially submerged in the liquid carried in the said box like structure, one of said electrodes having a submergeable area greater than the other.

4. In a device of the character described in combination, a liquid reservoir of non-conductive material, a rectangular box like member of non-

conductive material supported on the bottom of said reservoir, an electric vapor generator in said rectangular box like member, a non-conductive element on one of the outside walls of said box like member, said non-conductive element having an inclined passageway therein in communication with the interior of said box like element and said reservoir, a collapsible semi-spherical non-conductive element positioned over the upper end of said passageway and arranged, when collapsed, to force air into said passageway, whereby to prevent the electric current from the generator from reaching the liquid in the reservoir, a rod for supporting said semi-spherical element, a rocker arm for supporting such rod, a second rod supported by said rocker arm, and a float positioned in the said box like member and means for securing said float to said last named rod, said semi-spherical element having superimposed upon it a hollow spherical element the interior of which is in communication with the interior of said semi-spherical element.

5. The structure defined in claim 1, in which the rod supporting said float is threaded at the upper end and upon which threads are positioned a spool like nut, there being means connecting said nut and one end of said rocker arm whereby the travel of said rocker arm is controlled.

6. The structure defined in claim 1, in which the rod supporting said float is threaded at the

20
25

30

upper end and upon which threads are positioned a spool-like nut, there being means connecting said nut and one end of said rocker arm whereby the travel of said rocker arm is controlled; an offset rod secured to said nut and a locking element carried by one wall of said rectangular box like member, said locking element being adapted to frictionally engage said offset rod thereby said rocker arm and its associated elements may be held in predetermined position.

7. The structure defined in claim 1, in which said generator comprises a hollow rectangular member of a non-conductive material open at the bottom and having closely spaced electrodes supported on the interior thereof, one of said electrodes having a greater potential than the other, and a vapor discharge stack in communication with the interior of said generator and the atmosphere.
